UNITED STATES PATENT OFFICE.

RASSIE E. WICKER, OF CAMERON, NORTH CAROLINA.

ALARM FOR MOVING-PICTURE REELS.

Application filed October 25, 1923. Serial No. 670,787.

To all whom it may concern:

Be it known that I, RASSIE E. WICKER, a citizen of the United States, residing at Cameron, in the county of Moore and State 5 of North Carolina, have invented certain new and useful Improvements in Alarms for Moving Picture Reels; and I do hereby declare the following to be a full, clear, and exact description of the invention, such as 10 will enable others skilled in the art to which it appertains to make and use the same.

In the operation of moving picture apparatus, it is desirable for obvious reasons that the operator be advised when the end 15 of a film is about to be reached so that the next machine in order may be started or put in condition for instant service, whereby to prevent any appreciable break or interruption in the exhibition of a picture 20 embodying two or more reels.

The invention contemplates an alarm mechanism associated with the reel and including a detent for preventing operation of the alarm and which is normally held in 25 restraint by wind of the film upon the reel, said detent when released from restraint of the film automatically operating to release the alarm which gives warning that the end of the film is about to be reached so that the 30 operator may take proper action as occasion may require.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor 40 details of construction may be resorted to without departing from the nature of the invention.

Referring to the accompanying drawings forming a part of the application:

Figure 1 is a side view of the hub portion of a moving picture reel provided with an alarm mechanism embodying the invention,

Figure 2 is a sectional view on the line 2-2 of Figure 1, showing the parts on a 50 larger scale,

Figure 3 is a sectional view on the line 3-3 of Figure 2,

Figure 4 is a detail sectional view on the line 4-4 of Figure 2, and

Figure 5 is a perspective view of the detent.

Corresponding and like parts are referred to in the following description and designated in the several views of the drawings by like reference characters.

The numeral 1 designates the axle upon which a moving picture reel is generally mounted. The reel comprises a hub 2, side plates 3 and 4, a drum 5 and outwardly disposed arms 6 between which the film 7^a wound upon the drum 5 is received. In accordance with the present invention, a gong bell 7 is disposed within the drum 5 between the plates 3 and 4 and attached to the inner side of the drum. A sleeve 8 loosely mounted upon the hub 2, is provided with one or more hammers 9 disposed to strike the bell 7 and sound an alarm. One of the hammers 9 is provided with an offstanding arm 10 which is disposed within the path of a detent which normally prevents operation of the hammer and a sounding of an alarm. Movement of the hammer in one direction is prevented by a pin 11 which constitutes a stop 80 supported at its ends by the plates 3 and 4.

The detent is mounted at one side of the reel and comprises a pivot 12 and arms 13 and 14, the arm 14 being disposed to engage the arm 10 and the arm 13 being designed to extend across the reel and come between winds of the film 7^a to be normally held in restraint thereby. A spring 15 mounted upon the pintle 12 has one end 90 engaging the arm 14 and its opposite end engaging one of a pair of brackets 16 attached to the outer side of the plate 4 and in which the pintle 12 is mounted. The arm 13 is in the form of a loop and is bent intermediate its ends to admit of a portion 95 extending along the outer side of the plate 4 and a portion extending across the reel to be confined between winds of the film 7^a. The outer portion of the arm 13 is disposed a short distance from the drum 5 to admit 100 of a few winds of the film 7^a coming between it and the drum so that when the alarm is sounded by release of the arm 13, the operator is advised that the end of the film is near.

In practice, after the film 7^a has been wound about the drum 5 of the reel a few times, the detent is adjusted so that the arm 13 extends across the reel to be engaged by the subsequent winds of the film, as shown 110 most clearly in Figures 2 and 3. In this position of the detent, the arm 14 extends

across the path of the hammer 9 which is held between said arm and the stop 11. When the film is unwound from the reel and releases the arm 13 of the detent, the latter is moved by the spring 15 to the position indicated by the dotted lines in Figure 2 and is maintained in such position by the arm 14 engaging the inner side of the drum 5. The hammer 9 being released 10 is free to strike the bell 7 and sound an alarm, thereby giving warning that the end of the film is near so that the operator may take such action as the occasion may require.

What is claimed is:

- 15 1. An alarm for a moving picture reel, having a hub, comprising a bell carried by the reel, a hammer having a sleeve journaled on said hub a spring actuated detent pivotally mounted at one side of the reel comprising an arm adapted to engage the hammer and an arm to be confined between winds of the film upon the reel and releasable when the film is unwound to a predetermined extent from the reel to free the 25 hammer which operates to sound an alarm.
2. An alarm for moving picture reels, comprising a bell positioned within and secured to the drum of the reel for movement therewith, a hammer pivoted to the 30 hub of the reel for movement with respect to the drum in the plane of rotation thereof, means adapted to prevent the pivotal movement of the hammer in one direction with

respect to the drum, and a detent carried by the reel and normally held in restraint by the film wound thereon and engaging the hammer to prevent pivotal movement thereof in the reverse direction with respect to the drum and releasable when the film is unwound to a predetermined extent 40 from the reel to free the hammer for pivotal movement in said reverse direction to sound the alarm.

3. An alarm for moving picture reels, comprising a bell positioned within and movable with the reel, a hammer positioned within the reel and mounted for movement with respect to the reel in the plane of rotation thereof, means adapted to prevent the movement of the hammer in one direction with respect to the reel, and a detent carried by the reel and normally held in restraint by the film wound thereon and engaging the hammer to prevent movement thereof in the reverse direction with respect to the reel and releasable when the film is unwound to a predetermined extent 50 from the reel to free the hammer for pivotal movement in said reverse direction to 55 sound the alarm.

In testimony whereof I affix my signature in presence of two witnesses.

RASSIE E. WICKER.

Witnesses:

ROSWELL E. WICKER,
EDWARD T. VENO.
